(57)

CLAIM

The ornamental design for a projector, as shown and described.

DESCRIPTION

FIG. 1 is a top, front and right perspective view of a projector showing my new design;

FIG. 2 is a bottom, rear and left perspective view thereof;

FIG. 3 is a top, rear and right perspective view thereof;

FIG. 4 is a front view thereof;

FIG. 5 is a rear view thereof;

FIG. 6 is a top plan view thereof;

FIG. 7 is a bottom plan view thereof;

FIG. 8 is a right side view thereof;

FIG. 9 is a left side view thereof;

FIG. 10 is a top, front and right perspective view of the projector showing the design, with a lens directed to a first direction;

FIG. 11 is a bottom, rear and left perspective view thereof;

FIG. 12 is a front view thereof;

FIG. 13 is a rear view thereof;

FIG. 14 is a top plan view thereof;

FIG. 15 is a bottom plan view thereof;

FIG. 16 is a right side view thereof;

FIG. 17 is a left side view thereof;

FIG. 18 is a top, front and right perspective view of the projector showing the design, with the lens directed to a second direction;

FIG. 19 is a front view thereof;

FIG. 20 is a top plan view thereof;

FIG. 21 is a right side view thereof;

FIG. 22 is a top, front and right perspective view of the projector showing the design, with the lens directed to a third direction;

(Continued)

FIG. 23 is a bottom, front, and left perspective view thereof;
 FIG. 24 is a front view thereof;
 FIG. 25 is a top plan view thereof;
 FIG. 26 is a bottom plan view thereof;
 FIG. 27 is a right side view thereof;
 FIG. 28 is a top, front and right perspective view of the projector showing the design, with the lens directed to a fourth direction;
 FIG. 29 is a bottom, rear and left perspective view thereof;
 FIG. 30 is a front view thereof;
 FIG. 31 is a top plan view thereof;
 FIG. 32 is a bottom plan view thereof;
 FIG. 33 is a left side view thereof;
 FIG. 34 is a top, front and right perspective view of the projector showing the design, with the lens directed to a fifth direction;
 FIG. 35 is a bottom, front and left perspective view thereof;
 FIG. 36 is a front view thereof;
 FIG. 37 is a top plan view thereof;
 FIG. 38 is a bottom plan view thereof;
 FIG. 39 is a right side view thereof;
 FIG. 40 is a top, front and right perspective view of the projector showing the design, with the lens directed to a sixth direction;
 FIG. 41 is a bottom, front and left perspective view thereof;
 FIG. 42 is a front view thereof;
 FIG. 43 is a top plan view thereof;
 FIG. 44 is a bottom plan view thereof;
 FIG. 45 is a right side view thereof; and,
 FIG. 46 is a top, front and right perspective view of the projector showing the situation that a lens body is removed. The design of a lens of the projector as the lens transitions from any one of the first to the sixth directions to another of the first to the sixth directions forms no part of the claimed

design. The broken lines illustrate portions of the projector and form no part of the claimed design.
